UNITED STATES PATENT OFFICE.

ARTHUR B. GOODSPED, OF CHESTER, CONNECTICUT.

OIL BURNER.

Application filed June 6, 1924. Serial No. 718,229.

In another application of the present applicant for Letters Patent of the United States Ser. No. 655,386, filed August 3, 1923, there are shown and described certain improvements in oil burners. In that application a requirement was made on the part of the Commissioner of Patents for division on the ground that the claims were drawn to several independent inventions. The present application is made primarily for the purpose of complying with that requirement and for covering one of such independent inventions, but in the time which elapsed between the filing of said earlier application and the making of such requirement for division, the construction which formed the subject matter of said earlier application as filed, was further developed and perfected and the present application, therefore, while covering the original independent invention, is based upon the perfected construction and is addressed in part to the perfected features. The invention which is the subject of this application is concerned particularly with the control of the supply of oil and water.

In the operation of the structure shown in said earlier application, both the oil admission valve and the water admission valve remain closed until pressure has been developed through the generation of steam by the heat of the starting lamp. During the period of such development of pressure, there was sometimes a more or less fluctuating and spasmodic flow of oil and water so that it was not possible always to bring about the constant and governable supply of oil and water necessary to a uniform and constant accumulation of pressure. Furthermore, the fluctuation of flow retarded materially the prompt starting of the burner by reason of an interrupted temperature tension. This difficulty has been overcome, in the present instance, by the provision of improved automatic devices which, although operating in substantially the same manner as the former devices, have been so designed as to prevent the fluctuation of flow and spasmodic action. These improved devices and other features of improvement in connection with the control of the supply of oil and water to the burner, will be described more particularly hereinafter with reference to the accompanying drawings in which—

Figure 1 is a view mainly in elevation but partly in vertical section showing the im-

proved burner and, in connection therewith, the improved devices for controlling the supply of oil and water to the burner, the fuel pressure regulator and the automatic drain control being broken away.

Figure 2 is a view in elevation, partly in vertical section and on a larger scale, of the controlling devices shown in Figure 1 as seen from the same point of view.

Figure 3 is a view of the devices shown in Figure 2, partly in elevation and partly in vertical section, as seen from the right hand in Figure 1, with the fuel pressure regulator and the automatic drain control in section.

Figure 4 is a detail view in elevation of some of the parts shown in Figure 3 as seen from the opposite direction.

The fuel oil is supplied from any suitable source, under pressure or by gravity, through a pipe *a*, the pressure being regulated by devices to be described and the flow being controlled by a valve indicated generally at *b*, the construction and operation of which will also be described hereinafter.

From the valve *b* the oil is conducted through a pipe *a'* which is provided with a valve *a²* and is tapped into a base *c*, shown in Figure 1, the base being channeled as at *c'*. The base is also preferably formed, as before, with a conical seat *c²* to receive a conical liner *d*, which in turn is formed with a conical seat *d'* to receive a conical member *e* which supports the burner tip *e'*. The liner *d* is channeled as at *d²* and the burner support is channeled as at *e²* to permit the oil to be delivered to the orifice *e³* of the burner tip. The present invention is not concerned with the particular construction of the burner parts and the same therefore will not be described in detail herein, reference being had to the application above mentioned, Serial No. 655,386, and to another application Serial No. 718,230 filed June 6, 1924, in which the construction of the burner is more particularly described. For the purpose of insuring the flow of oil to the controlling devices at a uniform head there may be connected into the oil supply pipe *a*, as shown at *a³* in Figures 1 and 2, a float valve, the construction and operation of which are well understood and require no detailed description herein. For the further purpose of regulating the pressure of the oil at the burner there is also provided a pressure regulating device to be described.

Water is supplied, from any suitable

source, under pressure or by gravity, through a pipe g , which may also have connected into it, as indicated at g^20 , a float valve, also of ordinary construction and operation and therefore not necessary to be described herein. The flow of water is controlled, so as to permit or prevent the passage of water, by a valve indicated generally at b' , the construction and operation of which will be described hereinafter. From the valve b' the water is conducted by a pipe g' provided with a stop cock g^* , through a channel g^2 in the base c , whence it is delivered, as described in the other applications above mentioned, to a steam generator indicated at h . From the latter superheated steam is delivered, as described in said applications, to a chamber about the burner tip e' .

In order that the pressure under which the fuel oil is delivered at the burner tip may be regulated, within the maximum determined by the uniform head under which the fuel oil is delivered to the controlling and regulating devices, there is provided a pressure regulating device shown generally at s in Figures 3 and 4. This comprises a float valve tank s' having therein a float s^2 and a valve s^3 actuated thereby for controlling the inlet of oil to the tank. Oil is delivered to the tank s' from the pipe a through a pipe a which has swiveled connections with the pipe a and with the tank s' , at a^5 and a^6 , and oil is returned from the tank s' to the continuation a^7 of the oil pipe a through a pipe a^8 which has swiveled connections at a^9 and a^{10} with the outlet of the tank s' and the pipe extension a^7 . Between the swivel connections a^5 and a^9 there is interposed a pipe section a^{11} which is plugged so as to prevent the passage of oil therethrough, serving only as a support for the parts above it. In the pipe continuation a^7 there is interposed a stop valve a^{12} for the purpose of cutting off the delivery of oil to the controlling valve b when required. The described connections permit the tank s' to be raised or lowered as conditions may determine for the purpose of regulating the pressure at which the oil is delivered to the regulating valve b and therefore the pressure at which the oil is delivered at the burner tip. In order that the pressure regulating tank s' may be raised or lowered and sustained at the determined height there is provided a hand wheel s^4 on a shaft s^5 which carries a worm s^6 in engagement with a worm wheel s^7 on the shaft s^8 on which is fixed an arm s^9 which in turn engages, through a swiveled and sliding connection s^{10} , the swiveled pipe section a^8 . It has been found that in place of the form of valve shown in the application Serial No. 655,386 it is desirable to substitute a lap sleeve valve which is controlled by the pressure developed in the steam generator h , and it has also been found desirable to con-

trol the delivery of water to the generator by a lap sleeve valve. In the embodiment of the invention illustrated in the application last mentioned both the oil controlling valve and the water controlling valve were actuated by a single diaphragm, to the chamber of which steam pressure from the generator was admitted through a special connection provided for the purpose. It has been found desirable, however, to provide for the actuation of each valve a separate diaphragm, the pressure in the generator being communicated to the common chamber between the two diaphragms through a connection to the pipe through which water is delivered from the water valve to the generator, it being obvious that the water in the water system is subject to the pressure of the steam developed in the generator and serves as a convenient means of transmission of the pressure from the generator to the diaphragm chamber. The two diaphragms i and i' are shown as supported in a suitable housing i^2 , forming between them a diaphragm chamber which is connected through suitable pipe connections g^6 and g^7 , with the pipe g' by which water is delivered from the water valve b' to the generator. A spider i^3 is interposed between the two diaphragms to prevent excessive deflection of either.

The two valves, shown generally at b and b' , are identical in construction and a description of one will suffice for both, the same reference characters being employed to indicate like parts. The casing i^2 is formed, at each side, with a cylinder i^4 which has a removable head i^5 and lining i^6 . Within the lining is a sleeve valve i^7 which has at i^8 a circumferential channel through which, according to the position of the sleeve oil is permitted to flow from the inlet of the valve to the outlet from which it is delivered to the pipe a' or is cut off. The sleeve valve i^7 is secured to the corresponding diaphragm i or i' and receives within it a pull rod i^9 which has at i^{10} a swiveled connection with the sleeve valve. The rod also carries a coiled spring i^{11} which, abutting at one end against the head i^5 of the cylinder and at the other end against a collar on the rod, provides the pressure against which acts the pressure in the diaphragm chamber. It will be understood that as the pressure in the diaphragm chamber varies the sleeve valve i^7 will be moved to permit or prevent the flow of oil to the burner or of water to the generator as the case may be.

In order to permit the necessary flow of oil or water in beginning the operation of the burner and before sufficient pressure has been established in the generator, the valves b and b' should be opened and held open until the working pressure is established. For this purpose each rod i^9 is formed with a shoulder i^{12} for engagement by a weighted

latch i^{13} which is raised by hand into engagement with the rod when the rod is pulled out at starting. When the pressure has been established in the diaphragm chamber and the sleeve valve i^7 is pushed out by the diaphragm under the influence of the pressure in the chamber the rod i^8 is pushed out and releases the latch i^{13} which then falls by its own weight.

10 Any oil which may work past the oil sleeve valve into the space between the diaphragm i and the housing on that side may be drained off through a drain pipe i^{14} into the partitioned base pan t , a similar drain pipe i^{15} being provided for the drainage of water which may escape around the water sleeve valve. Other drain pipes i^{16} and i^{17} are provided at the other ends of the cylinders i^4 .

20 The drains i^{14} , i^{15} , i^{16} , i^{17} are open drains, but for the prompt removal of water of condensation from the diaphragm chamber, which is subject to pressure, it is desirable to provide an automatic drain valve controlled by the pressure in the diaphragm chamber. For this purpose there is connected into the water pipe system below the diaphragm chamber, as shown particularly in Figure 3, a valve casing v provided with a port v' through which water may escape into the base t and a valve v^2 of large area which is held to its seat by its own weight and by a spring v^3 . The valve is supported and lifted when the pressure falls through its stem v^4 by a weighted arm v^5 which, at the time of starting and until working pressure has been developed, is supported by a weighted latch v^6 . It will be understood that until the working pressure has been developed, the valve v^2 should be held on its seat. When such working pressure has been developed, the latch v^6 is disengaged manually.

25 It is desirable that both the oil pipe system and the water pipe system, between the controlling valves and the burner tip and generator, shall be drained of oil and water respectively when the oil and water controlling valves have been closed and also when the 30 operation of the burner has ceased for any accidental reason, as if the supply of oil or of water gives out or the burner is extinguished. Automatic drain valves, under the control of pressure in the generator and therefore in the diaphragm chamber, are accordingly provided as indicated at w and w' . The construction and operation of the 35 automatic drain valve for the water pipe system is the same as that of the automatic drain valve for the oil pipe system and description of the latter will therefore suffice, the same reference characters being employed to indicate like parts so far as they are shown in both. Connected to the pipe system is a centrally bored plug w^2 against

which, under the pressure of a spring w^3 , bears a valve w^4 supported by a sleeve w^5 mounted on the plug w^2 and provided with ports w^6 . A forked lever w^7 bears at its lower, forked end w^8 against the valve w^4 and at its upper end, w^9 , is engaged by the collar i^{12} on the end of the pull rod i^9 . The lever w^7 is so nearly balanced that the spring w^3 suffices to hold the valve w^4 against the plug w^2 under ordinary conditions of operation, when the diaphragm i^{10} is subject to the working pressure and the rod i^9 is pushed outwardly, but when, for any cause, the pressure in the diaphragm chamber falls materially and, the diaphragm i or i' , as the case may be, being relieved of pressure, the sleeve valve i^7 and with it the rod i^9 are moved toward the center of the diaphragm chamber by the spring i^{11} , the collar i^{12} of the rod i^9 rocks the lever w^7 upon its axis and moves the valve w^4 against the pressure of the spring w^3 thereby permitting all of the oil, or water, as the case may be, in the connected pipe system to be discharged into the base pan.

30 Reference has been made above to the regulation, through the raising or lowering of the tank s' , of the pressure under which the oil is delivered to the burner tip. It is desirable also to provide for regulation of the flow of water to the generator in accordance with the variation of pressure of the oil and at the same time to provide for independent adjustment of the flow of water to suit the conditions of operation. To meet these requirements there is inserted in the water pipe g' , below the water controlling valve b' , a water regulating valve g^8 , the stem of which carries an arm g^9 which has pivotally connected thereto at its upper end an arm g^{10} held yieldingly downward by a spring g^{11} . The arm g^{10} carries a rack bar g^{12} which engages a gear g^{13} on the shaft s^8 of the worm wheel s^7 . Thereby, as the tank s' is raised or lowered and the pressure or head of the oil is increased or diminished, the valve g^8 is opened more or less and the flow of water is increased or diminished. To adjust the flow of water to suit different conditions the rack bar g^{12} is raised out of engagement with the gear g^{13} and is moved to open the valve g^8 more or less as may be required.

35 In the embodiment of the invention shown in the application Serial No. 655,386, a special filler for the generator is provided, but in the present instance, for greater convenience in starting, there is provided a water by-pass g^{14} , connected to the water pipe g above the valve b' and to the water pipe g' below the valve b' and having a valve g^{15} . By opening the valve g^{15} and at the same time opening the valve g^8 in the pipe g' , near the generator, the air in the pipe system is permitted to escape and the requisite amount of water is introduced into the gen- 40

erator, the valve g^5 being closed as soon as the air is expelled. In the operation of the burner, the regulating wheel s^4 is turned to lower the tank s' until the pointer on the 5 swiveled pipe a^4 stands at the point marked "shut-off" on the scale a^{14} . The diaphragm drain valve v is held in closed position by the spring v^3 , the weighted lever b^5 being held up by the latch v^6 . The oil and water 10 having been admitted to the respective float valve tanks a^3 and g^{20} the valve pull rods i^9 are pulled out and engaged by the latches i^{13} . The valve e^{15} in the water by-pass g^{14} is opened and water is permitted to flow 15 through the by-pass to fill the water pipe system and introduce into the generator h sufficient water for starting, the vent cock g^3 having been opened. It will be understood that when the water by-pass g^{14} is opened 20 more or less water will enter the diaphragm chamber, due to the head of the starting water in the generator, thereby compressing to a like extent the air which is scrapped in the diaphragm chamber above the water. 25 The starting lamp k having been filled is then lighted and presently sufficient heat is developed to generate steam in the generator. As the steam is generated and pressure is developed in the diaphragm chamber the 30 water and oil controlling valves will be moved outward from the partly open position in which they are held by the latches i^{13} and the latches will drop of their own weight. Working pressure having now 35 been developed the regulating wheel s^4 is turned until the pressure or head of the oil and the flow of the water are such as the operating conditions require.

The valve a^2 is provided for the purpose 40 of regulating the flow of oil from the valve b and therefore from the tank s' , thereby, if the orifice of the valve a^2 through which the oil flows is reduced the range of movement of the tank s' , to regulate the pressure is increased, while if the orifice of the valve a^2 is 45 increased the range of movement of the tank s' is decreased. This makes it possible to maintain readily the proper ratio of delivery of oil and water under all conditions 50 of operation.

It will be understood that various changes in details of construction and arrangement can be made to suit different conditions of use and that, except as pointed out in the 55 claims, the invention is not limited to the particular construction and arrangement shown and described herein.

I claim as my invention:

1. In an oil burner, the combination of a 60 burner tip, means to supply oil thereto, a lap sleeve valve to control the flow of oil to the burner tip, a steam generator, means influenced by the pressure in the generator to control the valve, manually controlled means to move the valve to open position, and a

weighted latch to engage said means and hold the valve in open position, the latch being released and disengaged by the continued movement of the valve under the influence of pressure in the generator. 70

2. In an oil burner, the combination of a burner tip, means to supply oil under pressure, means to supply steam to the burner tip, a valve to control the flow of oil to the burner tip, devices whereby said valve is closed by a reduction of the steam pressure, a pipe system to conduct oil from the valve to the tip, a drain valve to drain the oil from the pipe system, and means in operative relation with the oil control valve to open the drain valve as the oil control valve closes, said means affording a degree of independent movement of one valve with respect to the other. 75

3. In an oil burner, the combination of a burner tip, means to supply oil under pressure, means to supply steam to the burner tip, a valve to control the flow of oil to the burner tip, devices whereby said valve is closed by a reduction of the steam pressure, a pipe system to conduct oil from the valve to the tip, a drain valve to drain the oil from the pipe system, and a lever in operative engagement with the oil control valve and with the drain valve to open the latter as the former closes, said means affording a degree of independent movement of one valve with respect to the other. 90

4. In an oil burner, the combination of a burner tip, means to supply oil thereto, a steam generator, means to supply water to the generator, a lap sleeve valve to control the flow of water to the generator, means influenced by the pressure in the generator to control the valve, manually controlled means to move the valve to open position, a latch engaging said means to hold the valve in open position, and pressure controlled means to disengage the latch. 100

5. In an oil burner, the combination of a burner tip, means to supply oil thereto, a steam generator, means to supply water to the generator, a lap sleeve valve to control the flow of water to the generator, means influenced by the pressure in the generator to control the valve, manually controlled means to move the valve to open position, and a weighted latch to engage said means and hold the valve in open position, the latch being released and disengaged by the continued movement of the valve under the influence of pressure in the generator. 110

6. In an oil burner, the combination of a burner tip, means to supply oil thereto, a steam generator, means to supply water to the generator, a valve to control the flow of water to the generator, pressure controlled means to operate said valve, a pipe system to conduct water from the valve to the generator, a drain valve to drain the water 115

from the pipe system, and means in operative relation with the water controlled valve to open the drain valve as the water controlled valve closes, said means affording a degree 5 of independent movement of one valve with respect to the other.

7. In an oil burner, the combination of a burner tip, means to supply oil thereto, a steam generator, means to supply water to 10 the generator, a valve to control the flow of water to the generator, pressure controlled means to operate said valve, a pipe system to conduct water from the valve to the generator, a drain valve to drain the water from 15 the pipe system, and a lever in operative engagement with the water controlled valve and the drain valve to open the latter as the former closes, said means affording a degree 20 of independent movement of one valve with respect to the other.

8. In an oil burner, the combination of a burner tip, means to supply oil thereto under pressure, a valve to control the flow of oil to the burner tip, a steam generator, means 25 influenced by the pressure in the generator to control the valve, a tank interposed in the means to supply oil and capable of being raised and lowered, swiveled pipe connections by which the tank is supported and through 30 which oil is supplied to the tank and from the tank to the burner tip, and means to raise and lower the tank.

9. In an oil burner, the combination of a burner tip, means to supply oil thereto under 35 pressure, a valve to control the flow of oil to the burner tip, a steam generator, means influenced by the pressure in the generator to control the valve, a tank interposed in the means to supply oil and capable of being 40 raised and lowered, swiveled pipe connections by which the tank is supported and through which oil is supplied to the tank and from the tank to the burner tip, a swinging arm engaging one of said swiveled pipe connections, and manually operated means to 45 change the position of the arm.

10. In an oil burner, the combination of a burner tip, means to supply oil thereto under pressure, a valve to control the flow of oil 50 to the burner tip, a steam generator, means influenced by the pressure in the generator to control the valve, a tank interposed in the means to supply oil and capable of being

raised and lowered, swiveled pipe connections by which the tank is supported and through 55 which oil is supplied to the tank and from the tank to the burner tip, a swinging arm engaging one of said swiveled pipe connections, a shaft to which the arm is attached, a worm wheel fixed on the shaft and a manually operated worm engaging the worm wheel.

11. In an oil burner, the combination of a steam generator, means to supply water thereto under pressure, a valve to control the 60 flow of water to the generator, means influenced by the pressure in the generator to control the valve, a valve to regulate the flow of water, an arm fixed to the stem of the valve, a second arm pivotally connected to 65 the first and carrying a rack bar, a gear engaged by the rack bar and means to rotate the gear.

12. In an oil burner, the combination of a burner tip, means to supply oil thereto under 70 pressure, a valve to control the flow of oil to the burner tip, independent means to regulate the pressure under which the oil is supplied to the burner tip, a steam generator, means to supply water thereto under pressure, a 75 valve to control the flow of water to the generator, and independent means to regulate the flow of water, said independent means to regulate the oil pressure and said independent means to regulate the flow of water being 80 operatively connected to move together, and said independent means to regulate the flow of water being capable of independent 85 adjustment with respect to the independent means to regulate the oil pressure. 90

13. In an oil burner, the combination of a burner tip, means to supply oil thereto under pressure, a valve to control the flow of oil to the burner tip, a steam generator, a diaphragm chamber and diaphragm to control 95 said valve, means to transmit pressure from the generator to the diaphragm chamber, a drain valve subject to the pressure in the diaphragm chamber, a weighted lever engaging the valve to open the same when the pressure 100 in the diaphragm falls, and a manually operated latch to hold the weighted lever against action.

This specification signed this 3d day of June A. D. 1924.

ARTHUR B. GOODSPEED.
